Baden, Switzerland, a joint-stock company of
Switzerland

Application March 16, 1934, Serial No. 715,806
In Germany March 31, 1933

14 Claims. (Cl. 175—363)

This invention relates in general to improvements in electric valve control systems and more particularly to means for impressing positive voltage impulses of short duration on the control electrodes of a valve.

Electric valves are frequently associated with inductive windings and suitable circuits therebetween to constitute different current converting systems such as alternating current rectifying direct current inverting, frequency converting and other systems. In such instances, it is frequently desirable that the control electrodes receive voltages which are negative relative to the cathode, during comparatively long intervals, and recurrently receive positive voltage impulses of comparatively short duration compared to the duration of the cycle of the corresponding anode voltage. More particularly, in direct current inverting systems each anode is positive with respect to the associated cathode during substantially the entire idling period of the anode, so that the periods of positive energization of the control electrodes must be comparatively short to avoid undesired release of the flow of current during the idling period of the anode. Such result is not easily obtainable when sinusoidal voltages are impressed on the control electrodes and it is, therefore, preferable to impress on the control electrode a non-sinusoidal voltage wave having for example a vertical front and having a tail presenting a non-sinusoidal shape. Such a voltage impulse may be obtained by means of circuits comprising reactors and auxiliary valves supplied with alternating current in relation with the voltage cycle of the anodes.

It is, therefore, one of the objects of the present invention to provide a control system for an electric valve in which the control electrodes of the valve are positively energized during intervals of short duration relative to the cycle of the anode voltage.

Another object of the present invention is to provide a control system for an electric valve in which the control electrodes of the valve receive voltages having vertical wave fronts.

Another object of the present invention is to provide a control system for an electric valve in which the control electrodes of the valve receive voltages having a non-sinusoidal wave tail.

Another object of the present invention is to provide a control system for an electric valve in which the control electrodes of the valve are energized from inductive means associated with auxiliary valve means.

Other objects and advantages will be apparent

from the following description when read in connection with the accompanying drawings, in which:

Fig. 1 diagrammatically illustrates one embodiment of the present invention applied to the control of an alternating current rectifying or direct current inverting system;

Fig. 2 is a diagram of some of the voltages and currents present in the circuits of the embodiment illustrated in Fig. 1;

Fig. 3 diagrammatically illustrates a portion of a modified embodiment of the present invention differing from the embodiment illustrated in Fig. 1 in the connections between the elements of the auxiliary circuits and in the method of regulation of the total current; and

Fig. 4 is a diagram of some of the voltages and currents present in the circuits of the embodiment illustrated in Fig. 3.

Referring more particularly to the drawings by characters of reference, reference numeral 6 designates an alternating current line herein represented as a three phase line which will be considered as a supply line, the operation of the system being described assuming that alternating current received thereby from line 6 is to be rectified and supplied to a direct current line 11, 12. Line 6 is accordingly connected with the primary winding 7 of a transformer 8 having a secondary winding 9 comprising a plurality of phase displaced portions arranged in any suitable manner, such portions being connected, for example, in star to form a neutral point connected with conductor 11. The different portions of winding 9 are severally connected with the anodes 13 of an electric valve 14 of any suitable type, such as a valve of the vapor type, having a cathode 16 connected with conductor 12. Valve 14 is provided with the usual ignition and excitation means which are well known and, therefore, not shown.

The flow of current through each anode 13 is controlled by means of a control electrode 17 associated therewith, such control electrode being energized at voltages of variable signs and magnitudes referred to the potential of cathode 16 as datum. The control potentials for control electrodes 17 are obtained from circuits receiving alternating currents from line 6 through a transformer 18 having a primary winding 19 connected with line 6 and a secondary winding 21. Winding 21 preferably comprises a plurality of phase displaced portions arranged in a manner similar to the arrangement of the phase portions of winding 9 and each supplying current to one of a plurality of circuits each comprising an auxil-

iary valve 22, inductive means such as a reactor 23, and resistance means such as a rheostat 24. In the embodiment illustrated in Fig. 1, the anodes of the valves 22 are directly connected with 5 winding 21 and the movable contacts of rheostats 24 are jointly connected with the neutral point of winding 21.

Each valve 22 is bridged by an associated circuit comprising an adjustable resistor 26 and a reactor 27. The voltage appearing across the terminals of each reactor 27 or a component thereof is impressed on the corresponding control electrode by suitable means such as a secondary winding 28 arranged on the core of reactor 27. The connection between each control electrode 17 and cathode 16 then comprises the usual current limiting resistor 29, a winding 28, the connection of the several control electrode circuits with cathode 16 being completed through 10 a common negative bias battery 31 if so desired. The several rheostats 24 are arranged to form part of a regulator 32 having an actuating system 33 energized from a shunt 34 inserted in conductor 12 and arranged to move the taps of 15 the rheostats against the action of suitable restraining means such as a spring 36.

In operation, the system being connected as shown and line 6 being energized, winding 9 impresses, on the several anodes 13, alternating 20 voltages of equal magnitudes but relatively displaced in phase, but the operation of only one particular anode 13 will be considered in detail. The voltage of such anode with respect to the neutral point of winding 9 may be represented 25 by curve 37 in Fig. 2, the circuit containing the corresponding valve 22, reactor 23 and rheostat 24 then receiving, from winding 21, a voltage in suitable phase relation with the anode voltage and represented by curve 38. Such voltage becomes positive at a time represented by point A 30 to cause the flow through valve 22, reactor 23 and rheostat 24 of a current which, if allowed to reach the steady state flow thereof, would follow a sine wave curve 39 lagging behind curve 38.

As will appear hereinafter, the flow of current through the circuit does not begin in the positive direction corresponding to the positive half wave at time A but begins at a somewhat later instant 35 B. The current wave is then represented by curve 40 when read with respect to an exponential curve 41 intersecting curve 39 at a point corresponding to time B, and having ordinates decreasing at a rate depending upon the relative values of the inductance of reactor 23 and the resistance of the portion of rheostat 24 in 40 circuit. Such flow of current continues until an instant C corresponding to the second intersection of curves 39 and 41. The flow of current then reverses but as a result of the valve action 45 of valve 22, the current must then also flow through resistor 26, reactors 27 and 23 and rheostat 24. The steady state current curve is then, accordingly, not the negative portion of curve 39 but another curve 42 instead as the current is 50 reduced in magnitude and is generally given a phase displacement as a result of the flow thereof through resistor 26 and reactor 27. The flow of current, which is then negative, follows curve 42 read with respect to an exponential curve 43 55 intersecting curve 42 a second time at a point corresponding to time D in the following cycle and following time B at an interval of one cycle. The flow of current occurs in the same way during the successive cycles of the voltage of line 6.

The ohmic voltage drop in resistor 26 and rheostat 24 is proportional at every instant to the current and may be subtracted from curve 38 to obtain a curve 44 representing the inductive voltage drop in reactor 23 during the interval BC 5 and in the reactors 27 and 23 during interval CD. During interval BC reactor 27 does not receive an appreciable current and the voltage drop thereof is therefore substantially zero. During interval CD the voltage drop in reactor 27 is 10 proportional to the ordinates of curve 44, the voltage drop in reactors 27 and 23 being in relation with the inductances of such reactors. The voltage drop across the terminals of reactor 27 is accordingly represented by a curve 45 following the axis during interval BC and proportional to curve 44 during interval CD. Such curve possesses a dissymmetric alternating current component and a direct current component, the alternating current component being impressed 15 in reverse direction on control electrode 17 by winding 28, the voltage thus transmitted being represented by curve 47 similar to curve 45 taken in opposite sign and read with respect to an axis 48 to eliminate the direct current component 20 thereof. The voltage represented by curve 47 suddenly passes from a negative value to a positive value at time C and control electrode 17 accordingly releases the flow of current through anode 13 at such time. Such operation is sequentially repeated for all the anodes of valve 14 during each cycle of the voltage of line 6 and valve 14 therefore delivers current to line 11, 12 at a voltage represented by curve 51.

If a battery 31 is utilized, curve 47 is to be 35 read with respect to an axis 49 distant from axis 48 by an amount representing the voltage of battery 31. Curve 47 becomes positive at a time corresponding to a negative portion of curve 38 and a positive portion of curve 37, the connections of winding 21 with the associated circuits being so adjusted that the voltages represented by curves 37 and 38 are in the proper phase relation. In the present embodiment it is assumed that it is desired to maintain the flow of current 40 through line 11, 12 at a substantially constant value. If the intensity of the current is below the desired value, spring 36 overcomes the action of element 33 and causes the regulator to increase the portions of rheostats 24 inserted in 45 the circuits thereof. The ratio of inductance to resistance of the valve circuit is, accordingly, decreased and the lag of the currents through reactor 23 and reactor 27 is decreased. Time C is advanced in the cycle of the voltage and the 50 flow of current through valve 14 occurs at an increased voltage. Such action continues until the output voltage of valve 14 is raised to an extent sufficient to bring the flow of current to the desired value. If the flow of current is 55 greater than desired, such flow is returned to the normal value thereof in a manner opposite to that above described.

The operation of the above described system when such system is utilized for inverting direct 60 current from line 11, 12 into alternating current supplied to line 6 will readily be deduced from the above description by any one skilled in the art and, therefore, does not need to be specifically described.

In a system such as described above, therefore, winding 9 and valve 14 constitute electric translation means connected with line 6, and the circuit comprising valve 22, inductance means 23 and resistance means 24 is connected to receive 70 75

an electromotive force similar to an electromotive force of winding 9 from winding 21 operating as a source of alternating current. The resulting current is controlled by means of valve 22. Resistance means 26 and inductance means 27 with the connections therefore constitute another circuit connected across valve 22. The connections between cathode 16 and the control electrode 17 constitute a load circuit on which winding 28 impresses a voltage component similar to the alternating component of the portion of the second circuit which consists of reactor 27. Battery 31, impresses on the load circuit a voltage effective to prevent the flow of current through valve 41 and which is overcome by the voltage of winding 28. Regulator 32 varies the value of rheostat 24 and therefore regulates the effect thereof for modifying the relation between the electromotive force of winding 21 and the current in the circuit supplied therefrom in response to an operating condition of the system, i. e. the magnitude of the current in line 11, 12.

In the embodiment illustrated in Fig. 3 the anode of each valve 22 is directly connected with the neutral point of winding 21 and is connected with cathode 16 through battery 31. The cathode of each valve 22 is connected with one of the phase portions of winding 21 through the corresponding reactor 23 and rheostat 24. Each control electrode 17 is connected with cathode 16 through a resistor 29, a reactor 27 and battery 31. Each reactor 23 is provided with a direct current saturating winding 51, the several windings being preferably serially connected across a source of direct current through the rheostat 52 of a regulator 53. Regulator 53 is similar to regulator 32 but is provided with only one rheostat and is energized in response to the magnitude of the voltage in line 11, 12 as a result of the connection of the actuating windings thereof across such line. The action of regulator 53 is to maintain the voltage of line 11, 12 at a substantially constant value and such line may therefore be utilized as a source of direct current for windings 51.

The operation of the control circuits of the present embodiment is readily understood by comparison of the circuits in Figs. 1 and 3. The modified voltage and current relations in the control circuits of Fig. 3 are shown in Fig. 4 in which the modified curves have been designated with the same reference numerals as the original curves of Fig. 2. As a result of the reversal of the connections of the valves 22, the interval CD, during which reactor 27 carries current, now occurs mostly during the positive portion of curve 38. The phase relation between curves 37 and 38 has been modified accordingly by suitable modification of the connections of winding 21. Reactor 27 being inserted in series in the circuit of control electrode 17, both the alternating current and the direct current component of the voltage thereof are impressed on the control electrode. The voltage of the control electrode is then represented by curve 46, read with respect to axis 49 if a battery 31 is utilized.

If the voltage of line 11, 12 is lower than the value desired therefor, regulator 53 decreases the amount of rheostat 52 inserted in the circuit thereof, thereby causing windings 51 to receive an increased current to increase the degree of saturation of the cores of reactors 23. The inductance of each reactor is thereby decreased and time C is caused to occur earlier in the voltage wave of line 6 to cause the output voltage of

valve 14 to increase. Such action continues until the voltage of the line has reached the desired value, whereupon regulator 53 remains in the position reached thereby. If the voltage of line 11, 12 is greater than the desired value such voltage is decreased in a manner opposite to that above described. 5

The system of the present embodiment is also suitable for inverting direct current from line 11, 12, the duration of positive impulses impressed on each control electrode 17 being reduced to any desired extent by suitable choice of the voltage of battery 31. In the present embodiment, regulator 53 operates in response to the magnitude of the voltage in line 11, 12 for varying the value 15 of reactor 23 to thereby regulate the effect of such reactors.

Although but two embodiments of the present invention have been illustrated and described, it will be apparent to those skilled in the art 20 that various changes and modifications may be made therein without departing from the spirit of the invention or from the scope of the appended claims.

It is claimed and desired to secure by Letters 25 Patent:

1. In a system for generating a periodic potential, a circuit including a source of alternating current, resistance and inductance means in said circuit, electric valve means controlling the flow of current through said circuit, another circuit connected across said valve means, impedance means in the second said circuit, a load circuit and means coupling the said another circuit with said load circuit for impressing thereon a voltage component similar to a component of the voltage across a portion of the second said circuit.

2. In a system for generating a variable potential, a circuit including a source of alternating current, resistance and inductance means in said circuit, electric valve means controlling the flow of current through said circuit, another circuit connected across said valve means, resistance and inductance means in the second said circuit, a load circuit, and means coupling the said another circuit with said load circuit for impressing thereon a voltage component similar to a component of the voltage across a portion of the second said circuit. 50

3. In a system for generating a variable potential, a circuit including a source of alternating current, resistance and inductance means in said circuit, electric valve means controlling the flow of current through said circuit, another circuit connected across said valve means, resistance and inductance means in the second said circuit, a load circuit, and means coupling the said another circuit with said load circuit for impressing thereon a voltage component 60 similar to a component of the voltage across the second said inductance means.

4. In a system for generating a periodic potential, a circuit including a source of alternating current, resistance and inductance means in said circuit, electric valve means controlling the flow of current through said circuit, another circuit connected across said valve means, resistance and inductance means in the second said circuit, a load circuit, means coupling the 70 said another circuit with said load circuit for impressing thereon a voltage component similar to a component of the voltage across the second said inductance means, and means for regu- 75

lating the effect of the first said resistance means.

5. In a system for generating a periodic potential, a circuit including a source of alternating current, resistance and inductance means in said circuit, electric valve means controlling the flow of current through said circuit, another circuit connected across said valve means, resistance and inductance means in the second said circuit, a load circuit, means coupling the said another circuit with said load circuit for impressing thereon a voltage component similar to a component of the voltage across the second said inductance means, and means for regulating the effect of the first said inductance means.

6. In a system for controlling the flow of electric current, an electric current supply line, electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, and means coupling the said another circuit with said control electrode and with said cathode for impressing therebetween a voltage component similar to a component of the voltage across a portion of the second said circuit.

7. In a system for controlling the flow of electric current, an electric current supply line, electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, and means coupling the said another circuit with said control electrode and with said cathode for impressing therebetween a voltage component similar to a component of the voltage across the second said inductance means.

8. In a system for controlling the flow of electric current, an electric current supply line, electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, means for impressing between said control electrode and said cathode a voltage effective to prevent the flow of current through the first said valve, and means coupling the said another circuit with said control elec-

trode and with said cathode for impressing therebetween a voltage component similar to a component of the voltage across a portion of the second said circuit to overcome the effect of the first said voltage.

9. In a system for controlling the flow of electric current, an electric current supply line, electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, and means coupling said another circuit with said control electrode and with said cathode for impressing therebetween a voltage component similar to a component of the voltage across the second said inductance means, and means responsive to an operating condition of the system for modifying the relation between said electromotive force and the current in the first said circuit.

10. In a system for controlling the flow of electric current, an electric current supply line, electric translation means connected with said line and including an alternating current winding and an electric valve having an anode with an associated control electrode and cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, and means coupling the said another circuit with said control electrode and with said cathode for impressing therebetween a voltage component similar to a component of the voltage across the second said inductance means, and means responsive to the magnitude of the current in one of said lines for modifying the relation between said electromotive force and the current in the first said circuit.

11. In a system for controlling the flow of electric current, an electric current supply line, electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve controlling the flow of current through said circuit, resistance and inductance means in said circuit, another circuit connected across the second said valve, resistance and inductance means in the second said circuit, means coupling the said another circuit with said control electrode and with said cathode for impressing therebetween a voltage component similar to a component of the voltage across the second said inductance means, and means responsive to the magnitude of the voltage of one of said lines for modifying the relation between said electromotive force and the current in the first said circuit.

12. In a system for controlling the flow of electric current, an electric current supply line, electric translation means connected with said line and including an alternating current winding 5 and an electric valve having an anode with an associated control electrode and a cathode, an electric current output line connected with said translation means, a circuit connected to receive an electromotive force similar to an electromotive force of said winding, a second electric valve 10 controlling the flow of current through said circuit, resistance and inductance means in said circuit, another circuit connected across the second said valve, resistance and inductance means in 15 the second said circuit, means coupling the said another circuit with said control electrode and with said cathode for impressing therebetween a voltage component similar to a component of the voltage across the second said inductance means, 20 and means responsive to an operating condition of the system for varying the value of the first said resistance means.
13. In a system for controlling the flow of electric current, an electric current supply line, 25 electric translation means connected with said line and including an alternating current winding and an electric valve having an anode with an associated control electrode and a cathode, an electric current output line connected with said translation means, a circuit connected to receive an electromotive force similar to an electromotive force of said winding, a second electric valve 30 controlling the flow of current through said
- 5 circuit, resistance and inductance means in said circuit, another circuit connected across the second said valve, resistance and inductance means in the second said circuit, means coupling the said another circuit with said control electrode and with said cathode for impressing therebetween a voltage component similar to a component of the voltage across the second said inductance means, and means responsive to an operating condition of the system for varying the 10 value of the first said inductance means.
14. In a system for controlling the flow of electric current, an electric current supply line, electric translation means connected with said line and comprising an alternating current winding 15 and an electric valve having a plurality of anodes with associated control electrodes and a cathode, an electric current output line connected with said translation means, a group of circuits each comprising an inductance, a resistance and an 20 electric valve connected to receive an electromotive force similar to an electromotive force of said winding, another group of circuits each comprising an inductance and a resistance severally connected across the second said valves, and 25 means severally coupling the said another group of circuits with said control electrodes and said cathode for impressing therebetween a voltage component similar to a component of the voltage across a portion of one of the second said 30 circuits.

ERWIN KERN.
